UNITED STATES PATENT OFFICE.

KARL POTSCHNER, OF DOVER, OHIO.

METHOD OF MAKING TOOLS.

Application filed April 26, 1924. Serial No. 709,303.

This invention relates to tools and more particularly to an improved method of making tools such as illustrated in my copending application Serial No. 616,327, filed February 1, 1923, and is a continuation in part of said copending application.

The objects of the invention are to provide an improved method of forming the frame portion of the wrench with a minimum of labor and expense.

The above and other objects may be attained by first providing a transverse hole in the blank from which the frame member is made, this hole being located at a predetermined point and acting as a key to all subsequent operations.

Two cutting operations are next performed, the cutters being moved into the metal from opposite sides of the frame, two slight slotting, cutting or punching operations removing corners of the metal left by the cutters, after which a broaching, key-seating or other cutting tool is passed through the slot thus formed to widen a portion thereof, providing guideways or tracks.

The method thus set forth in general terms is illustrated in the accompanying drawings, in which—

Fig. 1 is a side elevation of the blank, from which the frame portion of the tool is formed;

Fig. 2 is a similar view after the first operation of providing the transverse hole in the frame;

Fig. 3 shows the second operation performed by a cutter;

Fig. 4 shows the third operation which is also a cutting operation;

Fig. 5 shows the frame after the two triangular slotting, cutting, or punching operations;

Fig. 6 shows the frame after the guideway operation;

Fig. 7 is an edge elevation of the finished frame; and

Fig. 8 is a sectional view of a partially completed frame made under a slightly different method.

Similar numerals refer to similar parts throughout the drawings.

The wrench to which the invention pertains is illustrated in my copending application above referred to, and the present method concerns more particularly the frame member illustrated at 1, and provided

with an integral jaw 2 and an integral handle portion 3.

This frame has an opening through its central portion as shown at 4 to receive a lever, and is provided with the guideways or tracks 5 to receive a movable jaw operated by the lever, all of which is illustrated in the copending application above referred to, but which has no particular bearing upon the present application, excepting that the improved method includes the formation of the frame member to receive said other parts.

The blank shown in Fig. 1, may be formed by punching, forging or the like, and includes the frame portion 1, integral jaw 2 and handle portion 3.

The first operation comprises the forming of the transverse hole 6 in the frame portion of the blank by drilling, punching or the like at a predetermined point. The location of this transverse hole determines the finished shape of the frame portion and acts as a key to each subsequent operation. This hole may be forged in when the piece is forged, or punched when the piece is blanked.

The next operation is shown in Fig. 3, a cutter indicated in dot and dash lines at 7 being moved in the direction of the arrow or at right angles to the same, slotting the upper left hand portion of the frame as shown at 8, the cut extending into the transverse hole 6 as shown.

In the next operation, as shown in Fig. 4, a cutter shown in dot and dash lines at 9, is moved longitudinally of the tool in the direction of the arrow in said figure, or at right angles thereto, slotting the right side 95 of the tool as shown at 10, the cut extending into the transverse hole 6 and substantially meeting or overlapping the cut made by the cutter 7.

From an observation of Fig. 4, it will be seen that by providing the transverse hole 6, the substantially triangular shaped portion of metal indicated at 11, is thus removed.

In the next operation, the two substantially triangular portions of metal shown at 12 and 13, are removed by slotting, punching or broaching or other similar operations, leaving the straight edges 12^a and 13^a respectively, as shown in Fig. 5.

The guideways or tracks 5 are then formed through the slotted portion of the frame, by drawing a broaching tool, a saw,

a slotter, or the like through the same, the finished tool member being shown in Figs. 6 and 7.

From the above, it will be seen that the transverse hole 6 is the key to the operations, as it furnishes the locating point for each subsequent operation on the frame, and also removes the triangular portion of metal indicated at 11, which could not be removed 10 in any other way on a commercial manufacturing basis.

This transverse hole thus furnishes the key to the most practical and inexpensive method known for manufacturing the frame member for this class of tool out of one solid piece of metal upon a commercial basis. It furnishes an economical means of deepening the slot beyond the reach of a slotting cutter, in that it removes the triangular 20 portion of metal, indicated at 11, without removing the back wall. It furnishes an absolute and unvarying locating point for all subsequent operations upon this member.

Fig. 8 shows a partly completed frame member made by a slightly different method, 25 in which the transverse hole is not provided in the frame to start the operations.

In this form, the cutters 7 and 9 are operated in the directions indicated by the arrows 30 or at right angles thereto, in the manner above described, slotting the frame as shown at 8^a and 10^a in Fig. 8, leaving the two substantially triangular portions of metal 12^b and 13^b to be removed by broaching, slotting, 35 punching or other obvious method. It will be noted that in this form, a considerably greater amount of metal has to be removed at 12^b than is necessary in the method above described. However, this method eliminates 40 one operation, namely, the transverse hole.

The guideways or tracks may be afterwards formed by broaching, as indicated at 5 and as above described.

I claim:—

45 1. The method of forming a tool part, which consists in providing a blank comprising a frame portion having a jaw formed at one end and a handle integrally formed at the other end thereof, forming a transverse hole in said frame portion at a predetermined point, slotting the frame portion from opposite sides in a plane at substantially right angles to the hole, the cuts substantially meeting or overlapping one another and the transverse hole, and cutting away triangular portions of metal adjacent to the point where the cuts meet at the side opposite to the transverse hole, and broaching 50 or otherwise cutting a guideway in the inner walls of the opening.

60 2. The method of forming a tool part, which consists in providing a blank comprising a frame portion having a jaw formed at one end and a handle integrally formed at the other end thereof, forming a transverse hole in said frame portion at a predetermined point, slotting the frame portion from opposite sides in a plane at substantially right angles to the transverse hole, the cuts substantially meeting or overlapping, removing a substantially triangular portion of metal from between the point where the cuts meet and the jaw, and broaching or otherwise cutting a guideway in the inner walls of the opening.

65 opposite sides in a plane at substantially right angles to the hole, the cuts substantially meeting or overlapping one another and the transverse hole, and cutting away triangular portions of metal adjacent to the point where the cuts meet and adjacent to the points where the cuts meet the transverse hole.

70 3. The method of forming a tool part, which consists in providing a blank comprising a frame portion having a jaw formed at one end and a handle integrally formed at the other end thereof, forming a transverse hole in said frame portion at a predetermined point, slotting the frame portion from opposite sides in a plane at substantially right angles to the hole, the cuts substantially meeting or overlapping one another and the transverse hole, cutting away triangular portions of metal adjacent to the point where the cuts meet and adjacent to the points where the cuts meet the transverse hole.

75 4. The method of forming a tool part, which consists in providing a blank comprising a frame portion having a jaw formed at one end and a handle integrally formed at the other end thereof, forming a transverse hole in said frame portion at a predetermined point, slotting the frame portion from opposite sides in a plane at substantially right angles to the hole, the cuts substantially meeting or overlapping one another and the transverse hole, cutting away triangular portions of metal adjacent to the point where the cuts meet and adjacent to the points where the cuts meet the transverse hole, and broaching or otherwise cutting a guideway in the inner walls of the opening thus formed.

80 5. The herein described method of forming a tool part, which consists in producing a blank comprising a frame portion having a jaw integrally formed at one end and a handle integrally formed at the other end thereof, forming a transverse hole in said frame portion at a predetermined point, slotting said frame portion from opposite sides in a plane at substantially right angles to the transverse hole, the slot substantially meeting or overlapping, removing a substantially triangular portion of metal from between the point where the slot meets and the jaw, and broaching or otherwise cutting a guideway in the inner walls of the opening.

85 6. The herein described method of forming a tool part, which consists in producing a blank comprising a frame portion having a jaw integrally formed at one end and a handle integrally formed at the other end thereof, forming a transverse hole in said frame portion at a predetermined point, slotting said frame portion from opposite sides in a plane at substantially right angles to the transverse hole, the slot substantially meeting or overlapping, removing a substantially triangular portion of metal from between the point where the slot meets and the jaw, and broaching or otherwise cutting a guideway in the inner walls of the opening.

- the transverse hole, the slots substantially meeting or overlapping, removing a substantially triangular portion of metal from between the point where the slots meet and 5 the jaw, and removing triangular portions of metal from the points where the cutters meet the transverse hole, and broaching or otherwise cutting a guideway in the inner walls of the opening.
- 10 7. The method of forming a tool part, which consists in providing a blank comprising a frame portion having a jaw formed at one end and a handle formed at the other end thereof, forming a transverse hole in said 15 frame portion at a predetermined point, slotting the frame portion from opposite sides in a plane at substantially right angles to the hole, the cuts substantially meeting or overlapping one another and the transverse hole, and cutting away portions of metal 20 adjacent the point where the cuts meet at the side opposite to the transverse hole.
8. The method of forming a tool part, which consists in providing a blank comprising a frame portion having a jaw formed at one end and a handle formed at the other end thereof, forming a transverse hole in said frame portion at a predetermined point, slotting the frame portion from opposite 25 sides in a plane at substantially right angles to the hole, the cuts substantially meeting or overlapping one another and the transverse hole, and cutting away triangular portions 30 of metal adjacent to the point where the cuts meet and adjacent to the points where the 35 cuts meet the transverse hole.
9. The method of forming a tool part, which consists in providing a blank comprising a frame portion having a jaw formed at one end and a handle formed at the other 40 end thereof, forming a transverse hole in said frame portion at a predetermined point, slotting the frame portion from opposite sides in a plane at substantially right angles to the hole, the cuts substantially meeting or overlapping one another and the transverse hole, cutting away portions of metal 45 adjacent to the point where the cuts meet and adjacent to the points where the cuts meet the transverse hole, and broaching or 50 otherwise cutting a guideway in the inner walls of the opening thus formed.
10. The method of forming a tool part, which consists in providing a blank comprising a frame portion having a jaw formed at one end and a handle formed at the other end thereof, forming a transverse hole in said frame portion at a predetermined point, slotting the frame portion from opposite sides in a plane at substantially right angles to the hole, the cuts substantially meeting or 55 overlapping one another and the transverse hole, cutting away portions of metal adjacent the point where the cuts meet at the side opposite to the transverse hole, and broaching or otherwise cutting a guideway 60 in the inner walls of the opening thus formed.

In testimony that I claim the above, I have hereunto subscribed my name.

KARL POTSCHEINER.
